UNITED STATES PATENT OFFICE.

JOHN B. HADAWAY, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

INSOLE MACHINE.

Application filed July 5, 1919. Serial No. 308,855.

To all whom it may concern:

Be it known that I, JOHN B. HADAWAY, a citizen of the United States, residing at Swampscott, in the county of Essex and State 5 of Massachusetts, have invented certain new and useful Improvements in Insole Machines; and I do hereby declare the following to be a full, clear, and exact description of the invention, such as will enable others 10 skilled in the art to which it appertains to make and use the same.

The present invention relates to machines for operating upon insoles and more particularly to machines of this character employed 15 in connection with the manufacture of insoles having a fabric reinforcement applied thereto.

It is desirable that in insoles of this type and especially what are known as "Gem" 20 insoles the fabric shall be trimmed while or after applying the reinforcing material in such a manner that it is not exposed after the insole is subsequently incorporated in a boot or shoe.

One object of the present invention, accordingly, is to provide certain improvements in insole reinforcing machines to facilitate and increase the efficiency of the 25 fabric trimming operation.

With this object in view the several features of the invention consist in certain novel features of construction, combinations and arrangements of parts hereinafter described and claimed, the advantages of which 35 will be obvious to those skilled in the art from the following description.

In the accompanying drawings illustrating the preferred form of the invention, Figure 1 represents a side elevation of a machine embodying the several features of the 40 invention; Fig. 2 is a front elevation, partly in section, of the machine shown in Fig. 1; and Fig. 3 is a detail illustrating an elevation, partly in section, of the mechanism for feeding the trimming knife.

The illustrated embodiment of the invention is conveniently applied to the machine disclosed in the patent to Hadaway No. 614,860, November 29, 1898, and certain 45 essential parts of the present machine are identical in their construction and mode of operation with the machine shown in this patent. The insole is supported upon a rotary work table 10 journaled in a bracket 11 secured to the machine frame 12 and the work

support is rotated intermittently, to feed the work, through a ratchet wheel 14 and driving pawl 16. The driving pawl is oscillated at predetermined intervals from a feed lever 17 fulcrumed at 15 and having a cam roll 60 18 upon the upper end which is received in a cam path formed in the face 19 of the usual cam disc 20. This feed lever is connected to the driving pawl through a horizontal bell crank 22 having one arm which is operatively connected with the lower end of the feed lever through intermeshing gear segments 23 and a second arm pivoted to a link 25 which is connected at its opposite end to the pawl carrier 26. The reinforcing fabric 70 is molded over the lip of the insole by the usual under-former 30, an inside former 31, a feed former or feeding foot 32 and a stationary former 33, all as shown in the drawings. The feed former 32 is depressed into 75 engagement with the work and is then moved laterally to feed the work in unison with the movement of the rotary table 10 when it is thereafter elevated and the outside of the lip engaged by the stationary 80 former 33 which completes the molding of the reinforcing fabric in the usual manner. All of the above described parts of the machine, together with the mechanism for operating them, are identical with those shown 85 in the patent hereinbefore referred to and in consequence have been only briefly described.

It is an important desideratum in machines of this character that the reinforcing fabric shall be trimmed during its application to the insole to conform generally to the outline of the insole and in such a manner that the fabric shall be cleanly severed along the desired line without liability of subsequent exposure when the insole is incorporated in a boot or shoe. To avoid any possibility of the fabric later showing in the shoe, mechanism has been constructed for trimming the fabric along a line within the outer margin of the insole and the present invention contemplates the improvement of this trimming mechanism to ensure the proper trimming of the fabric without interference with the application of the fabric to the insole or damage to the body of the insole. To this end a single rotary trimming knife is arranged in operative relation to the feather of the insole when the insole is positioned upon the work support and is connected with the feeding mecha- 100 105 110

nism to trim the fabric during the return movement of the feeding foot while the sole is clamped in a stationary position. The lateral position of this trimming knife is gaged by the feeding foot and in such a manner that the fabric is trimmed at a uniform distance from the base of the lip, thus ensuring that a sufficient amount of fabric remains to properly reinforce the lip. As shown in Fig. 1, a cutting disc 40 is mounted upon the end of a shaft 42 journaled in bearings formed in a carriage 43. The carriage 43 is supported at opposite ends upon studs 45 and 46 mounted in the lower ends of arms 47 and 48. These arms are supported at their upper ends upon studs 49 and 50 and the arm 48 is provided with an upwardly extending boss 52 which is engaged upon opposite sides by adjusting screws 53 and 54 threaded, respectively, in stationary lugs 55 and 56. By varying the relative positions of the two adjusting screws 53 and 54, the knife may be shifted laterally and caused to assume the proper operative position relative to the feeding foot 32 so that the fabric is trimmed upon a line immediately back of the feeding foot and at a uniform distance from the outer face of the insole lip. The knife is continuously rotated during the operation of the machine by the driving shaft 60 having a hub 61 secured to the inner end and provided with a radial slot 62 which receives a rib 63 secured to the shaft 42, as shown clearly in Figs. 1 and 3. This construction serves to rotate the knife shaft 42 and still permits axial and transverse adjustments of the knife shaft relative to the drive shaft 60. Since the knife 40 is located above the table 10, a peripheral groove 64 is provided in the face of the table within which the rotating knife may enter when no work is in the machine and the table rises, under the influence of its spring within the bracket 11, and approaches the stationary former 33. This groove is indicated by dotted lines in Fig. 2.

The cutting movement of the knife in the line of feed is preferably imparted during the return movement of the feeding foot 32, that is, while the sole is held clamped between the work table and the stationary former. To this end the table feed lever 17 may conveniently be used as the actuator for the knife carriage 43, the stroke of this lever which moves the feed pawl 16 backward being employed to move the rotating knife to the right (Fig. 2) with the feeding foot 32 which is given a four-motion movement by mechanism connecting it with cam paths in the cam discs 68 and 69, all as described in said patent hereinbefore referred to. Accordingly the lower end of the table feed lever 17 is connected with the knife carriage 43 through a cross link 65 connected

at its opposite ends to the two members through ball and socket joints indicated at 66 and 67. It will be noted from an inspection of Figs. 2 and 3 that the studs 45 and 46 upon which the carriage 43 is mounted are elongated to permit transverse sliding movements of the carriage thereon. With this construction the cutting disc 40 is caused to move in unison with the feeding movements of the foot 32. Upon the advancing movement of the foot 32 to feed the work the disc moves therewith and no extension of the cut through the fabric takes place but upon the return movement of the foot, while the work is held stationary, the cutting disc 40 travels through the fabric and trims it upon a line within the edge of the sole.

In order to accurately gage the depth of cut made by the knife so that the latter shall cut through the fabric without cutting into and thus weakening the leather, the stud 45, upon which the forward end of the carriage is supported, is provided with an eccentric portion, as indicated in Fig. 1, whereby when the stud is turned, the knife is raised or lowered slightly with relation to the work table.

It will be recognized by those skilled in the art that the canvas trimming feature of the machine herein described is not limited in its use to a combination with bead forming instrumentalities, but will perform its function with equal facility if the inside canvas forming tool is disconnected or removed. In this event the machine may be employed as a canvas trimming machine for operating on previously reinforced soles.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. A machine for operating on reinforced insoles having, in combination, means for supporting and feeding the insole, a disc knife for trimming the reinforcing material, and means for rotating said knife and reciprocating it in the line of feed.

2. A machine for operating on reinforced insoles having, in combination, means for supporting and feeding the insole, including a four-motion feeding foot, a rotary knife for trimming the reinforcing material, and means for reciprocating said knife in the line of feed during its rotation in unison with like movements of the foot.

3. A machine for operating on reinforced insoles having, in combination, means for supporting and feeding the insole, including

- mechanism connected to and operating to advance said supporting means intermittently in the line of feed, a knife for trimming the reinforcing material and its carrier, and connections between said mechanism and the knife carrier for advancing said knife in the line of feed when said supporting means is advanced.
4. A machine for operating on reinforced insoles having, in combination, means for alternately advancing the sole and then clamping it against movement, a knife opposite the feather for trimming the reinforcing material along a line within the edge of the sole, and means for reciprocating said knife with the sole in its advance movement and then back to make a cut while the sole is held from movement.
5. A machine for operating on reinforced insoles having, in combination, means for supporting and feeding the insole, a disc knife opposite the feather for trimming the reinforcing material along a line within the edge of the sole, means for continuously rotating said knife, and means for reciprocating said knife in the line of feed during its rotation.
6. A machine for operating on reinforced insoles having, in combination, a work support, means for rotating said support step-by-step including a pawl and ratchet and an actuator for said pawl, a knife for trimming the reinforcing material and its carrier, and means connecting said actuator and knife carrier operating to advance the knife in the line of feed on the operative stroke of said pawl and return the knife to its initial position on the idle stroke of said pawl.
7. A machine for operating on reinforced insoles having, in combination, a work support, mechanism for feeding the work, a knife opposite the feather for trimming the reinforcing material along a line within the edge of the sole, and means controlled by the work feeding mechanism for reciprocating said knife in the line of feed.
8. In a machine for trimming reinforced ribbed soles, a gage constructed and arranged to bear against the sole rib, a continuously rotating disc knife opposite the feather for trimming the reinforcing material along a line at a predetermined dis-
- tance from the rib, and means for reciprocating said knife in its own plane during the cutting operation.
9. In a machine for trimming reinforced insoles, means for supporting and intermittently feeding the insole, a knife for severing the reinforce along a line inside the edge of the sole, means to gage the depth of cut to the thickness of the reinforce, and means for reciprocating said knife in the line of the cut.
10. A machine for operating on reinforced insoles having, in combination, means for alternately advancing the sole and then clamping it against movement, a disc knife for trimming the reinforcing material, means for continually rotating said knife, and means for reciprocating said rotating knife with the sole in its advance movement and then back to make a cut while the sole is held from movement.
11. A machine for operating on reinforced insoles having, in combination, a work support, mechanism for feeding the work, a disc knife opposite the feather for trimming the reinforcing material along a line within the edge of the sole, means for continually rotating said knife, and means controlled by the work feeding mechanism for reciprocating said rotating knife in the line of feed.
12. In a machine for trimming reinforced insoles, a disc knife for severing the reinforce along a line inside the edge of the sole, a shaft for said knife, means which may be actuated to move said shaft to adjust the depth of cut to the thickness of the reinforce, and means for reciprocating said knife in the line of the cut.
13. A machine for trimming reinforcing material lying on the feather of a ribbed insole having, in combination, an insole support constructed and arranged to sustain the feather at its margin, a gage constructed and arranged to bear against the rib, a single, continuously rotating disc knife opposite the feather and directly above said support for trimming the reinforcing material along a line spaced from the rib and devices by which said knife may be adjusted to vary the distance of the cut from the rib and also the depth of the cut.

JOHN B. HADAWAY.
